UNITED STATES PATENT OFFICE

ALBERT W. FRANKLIN, OF NEW YORK, N. Y.

NIGHT LAMP AND SWITCH THEREFOR

Application filed January 29, 1929. Serial No. 335,949.

This invention relates in general to an electric night lamp and switch therefor.

One of the objects of the invention is the provision of a plug member adapted to be screwed into an ordinary outlet socket and to receive an electric light and an auxiliary light of smaller candle power and a switch, all arranged so that when the switch is operated to extinguish the larger electric light 10 the smaller light is energized.

A further object of this invention is the provision of an electric switch which is exceedingly simple in construction, cheap to manufacture, and yet rugged and efficient in 15 use.

Another object of this invention is the provision of an electric switch having a body portion comprising three separable parts, contact members within the body portion, 20 and means for establishing circuit communication between the contacts.

A further object of this invention is the provision of a switch of such structure that the contacts provide circuit terminals and 25 also the spring resistance to the movement of the movable member of the switch.

A further object of this invention is the provision of a switch of this nature which may be easily adapted for use in connection 30 with the night light lamp by the removal of one part and the addition thereto of several others.

These and other objects, as will appear from the following disclosure, are secured by 35 means of this invention.

This invention resides substantially in the combination, construction, arrangement, and relative location of parts, all as will be described more fully hereinafter.

40 Referring to the drawings—

Figure 1 is a vertical central cross-sectional view through the switch;

Fig. 2 is a similar cross-sectional view taken at right angles to the view of Fig. 1;

45 Fig. 3 is a horizontal cross-sectional view taken on the line 3—3 of Fig. 1;

Fig. 4 is a vertical cross-sectional view taken on the line 4—4 of Fig. 3;

50 Fig. 5 is a perspective view of the movable switch handle;

Fig. 6 is an elevational view of the electric night lamp showing the plug member partly in cross-section;

Fig. 7 is a vertical longitudinal view taken on the line 7—7 of Fig. 6;

Fig. 8 is an enlarged cross-sectional view taken on the line 7—7 of Fig. 10;

Fig. 9 is an end view of the switch member adapted to receive the small electric light socket;

Fig. 10 is an end view of the other end of the switch; and

Fig. 11 is a side elevational view of the small electric light socket with the lamp therein.

The broad object of this invention is the construction of an electric night lamp in which a large and a small electric bulb cooperate in a circuit controlled by a special switch which, when the large electric lamp 70 is cut off, permits the small lamp to light up. The circuit is such that when the smaller lamp is lighted it is in series with the larger lamp and does not have sufficient current to cause the larger lamp to light up. 75

A secondary object of the invention is the provision of a switch, complete in itself, but adapted upon slight alteration to form the switch for the electric night lamp. The feature of this switch is that the spring contact 80 members through which the circuit is completed also offer resistance to movement of the switch handle which completes the circuit between the contact members.

Referring in detail to the drawings, the 85 switch is shown comprising a main body portion 1 recessed at each end and internally threaded at the recessed end. This construction leaves the central transverse wall 2 having passages 6 therein through which the 90 wires may be threaded. At each end of the body portion are provided the end members 3, 4 which have threads thereon to engage with the internal threads of the main body 95 1. When the parts are united they provide a small cylindrical switch with rounded ends 1. When the parts are united they provide a small cylindrical switch with rounded ends which are apertured so that the circuit wires may pass therethrough. The main body portion is provided with two holes extending through the wall thereof diametrically op- 100

posite to each other. They are disposed with respect to the transverse wall so that the switch handle 5 which extends therethrough is partially embedded in a semi-circular 5 groove extending across the transverse wall, as indicated at 2', Fig. 2. The switch handle 5 is cut away at its center to provide the reduced portion 7 having parallel sides.

Extending through the central hole in the 10 transverse wall are the two spring contact fingers 8 and 9 which are secured thereto by means of screws. Extending through the part 7 of the switch handle 5 is a contact pin 10 which is slightly shorter than the width 15 of the portion 7. At the other end of the flat portion 7 on each side thereof are the slight depressions 11. The spring fingers 8 and 9 are provided with indentations 13 and 12 properly arranged so that when the switch 20 handle is in one position they engage the depressions 11 and in the other position they contact with the contact pin 10. Thus, when the switch handle is in one position, electrical contact is made between them through the 25 part 7 thereof by means of contact pin 10. When the handle is in the other position the indentations on the spring fingers lie in the depressions 11 to hold the switch handle there. It will be apparent, therefore, that the spring 30 fingers act both to make contact and to provide the spring resistance to the movement of the switch handle.

The switch which has just been described in detail forms an integral part of the night 35 lamp disclosed in Figs. 6 to 11, inclusive. This night lamp comprises a plug and socket member having a hollow shell 15 on which is supported and insulated therefrom the contact 16. An outer casing 17 is provided 40 within which lies the insulating cylinder 16' for holding the shell 15 out of contact with the outer casing 17. The outer end of the shell 15 provides the plug by means of which the device is connected to an ordinary socket 45 outlet. The inside of the shell 15 at the lower end provides a socket to receive the large electric light.

A transverse wall 18 is mounted within the shell and is provided with the contact 50 terminal 19 and the spring finger 20. When a bulb is screwed into the socket shell 15 the bulb forces the spring finger 20 into contact with the contact 19. This plug, in other words, is intended to connect the night light 55 into a regular outlet and yet not interfere with its function of supporting and providing electric connections to the electric bulb. A wire 21 is connected to the contact 16 and a wire 22 is connected to the contact 19. These 60 two wires extend to and through the end cap 3 of the switch 1. When the switch 1, described in detail above, is employed in this night light structure its other cap 4 is removed and the shade 33 is substituted therefor. This shade is secured to the main body

of the switch 1 by means of a coupling member 31, as is clearly shown in Fig. 7, which is provided with openings to permit the escape of heat generated by the smaller bulb 40. The same screw 27 which holds the contact 12 in place in this form of the device also holds the small bracket 23 and causes it to make electrical contact with the spring contact 12. Secured to the bracket 23 by means of the machine screw 27 is the insulating disc 24 the metallic disc 25, and the insulating disc or button 26. The smaller socket shell 28 encircles the button 26 and is soldered to the metallic disk 25. The disc 25 has a small pigtail 29 which extends through a hole in the transverse wall 2 of the switch body and contacts with the metallic strip 30 which is connected to the spring finger 13 and to the wire 21. Thus the shell 28 is connected through disc 25, pigtail 29, contact strip 30, and spring contact 13 to wire 23 and is at the same time insulated from the bracket 23. The bracket 23 is in electrical contact with the spring contact 12, both of which are connected to the wire 22. An examination of this circuit will show that the small electric bulb 40 is in parallel with the spring contacts 12 and 13. These spring contacts 12 and 13 are in series with the wires 21 and 22 so as to control the flow of electric current to the larger bulb which fits into the socket shell 15. Thus when switch handle 5 is thrown in a position to complete the circuit to the larger bulb from wires 21 and 22 the small bulb is short-circuited and hence is not energized. Thus when the larger bulb is de-energized by breaking the circuit at the contacts 12 and 13 the smaller bulb 40 is in series with the larger bulb and is energized. The filament of the larger bulb forms a resistance in the circuit which prevents the destruction of the smaller bulb and since the smaller bulb takes but a little current the larger bulb will not be energized enough to give off any light.

By means of this exceedingly simple structure it is possible to provide an electric night lamp which gives sufficient illumination to permit one to move about in a darkened room without danger of injury and to make it easy to locate the switch which controls the large bulb. This simple device provides an electric night lamp for use in hallways, sick rooms, and the like.

From the foregoing disclosure it will be apparent that I have devised an exceedingly simple structure having highly useful purposes. The principles by means of which these purposes are accomplished may, of course, be embodied in a number of physical forms and I do not, therefore, desire to be strictly limited to the disclosure given for purposes of illustration but rather to the scope of the appended claim.

What I seek to secure by United States Letters Patent is:

A night lamp unit of the type described, comprising a standard plug for insertion in a standard socket, a tubular extension affixed to said plug, an outlet in said extension, a 5 transverse wall of insulating material in said extension forming the head of a standard lamp socket, an electrical connection between one contact of said socket and one contact of said plug, an electrical connection between 10 the other contact of said plug and one contact finger of a switch, an electrical connection between the other contact of said socket and the other contact finger of said switch a socket mounted on said switch the respective 15 contacts thereof being connected to the respective switch fingers of the switch, means for short-circuiting the switch fingers and the socket supported by the switch, the switch and socket thereon being physically separated 20 from the plug and socket unit.

In testimony whereof I have hereunto set my hand on this 28th day of January A. D., 1929.

ALBERT W. FRANKLIN.
